UNITED STATES PATENT OFFICE.

FRANK MORGAN HOWE, OF NEW YORK, AND CHARLES NAEGELI, OF LONG ISLAND CITY, NEW YORK

AIR-HEATING ATTACHMENT FOR FANS.

Application filed December 21, 1921. Serial No. 523,905.

To all whom it may concern:

Be it known that we, FRANK MORGAN HOWE and CHARLES NAEGELI, both citizens of the United States, residing in the city, county, and State of New York, and in Long Island City, county of Queens, State of New York, respectively, have invented certain new and useful Improvements in Air-Heating Attachments for Fans, of which the following is a full, true, and accurate description.

Our invention relates to an electric attachment for heating air and has as certain of its objects the provision of an attachment which is convenient in use and which will provide a comparatively concentrated current of warm air.

The novel features of our invention are pointed out with particularity in the appended claims. The invention itself, however, with further objects and advantages, will best be understood from the following description taken in connection with the accompanying drawing in which.

Fig. 1 is an elevation partly in section illustrating a heating attachment according to our invention applied to a fan of ordinary type.

Fig. 2 is a front view of the apparatus shown in Fig. 1.

Fig. 3 is an elevation of the attachment illustrated in Figs. 1 and 2 as it appears when detached from the fan.

Fig. 4 is a detail of the electrical connections for the heating element of the attachment illustrated in Figs. 1, 2 and 3.

Fig. 5 is a detail of the means for supporting the heating element of the attachment illustrated in Figs. 1, 2 and 3.

Figs. 6 and 7 are details of modified forms of center shields which may be substituted, according to our invention, for the shield illustrated in Figs. 1, 2 and 3.

In the drawing 1 is an electric fan which may be of any known or desired type for use in offices or household quarters. Fans of this type are, as is well known, ordinarily provided with a wire cage or shield 2 to protect persons and objects from coming in contact with the fan blades 3, 3 when the fan is in use. Shields 2 ordinarily comprise a rear ring 2^a in a plane at right angles to the axis of revolution of the fan blades and the front ring 2^b spaced from the ring 2^a and held in a

plane parallel to that of ring 2^a by means of 55 braces or connecting wires 4.

An attachment according to our invention comprises a cylinder 5, the rear portion 5^a of which is adapted to fit closely over the outside of the ring 2^b, cylinder 5 60 having internal shoulder 5^b which limits the movement of cylinder 5 on the ring 2^b. Secured to cylinder 5, at points 6, 6 are a plurality of coil springs 7, 7, the free ends of which are formed into hooks 8, 8 adapted 65 to be passed over the rear ring 2^a of the shield or guard 2, as illustrated in Fig. 1, and when the parts are in this position, the heating attachment is securely but removably held on the shield or guard 2. Supported by the cylinder 5 and extending forwardly therefrom is a hemispherical frame work 9 of wire or similar material. Supported on frame work 9 is a ring 10 of sheet metal or the like designed to support a heating coil 11 and we prefer to make the ring 10 of frusto conical form in order to concentrate the air from the fan into a stream of convenient cross-section. The heating coil or element 11 is conveniently disposed within the support 10 in an annular arrangement, being held at intervals by heat resistant insulating members 12, 12 which are secured to the band 10 by means of 70 screws 13 or other convenient means, the supports 12 preferably having apertures 14 therein through which the wire of the heating element 11 may be threaded. As clearly appears in Figs. 1 and 2 the wire of element 11 is coiled helically in order 75 to provide a large length of wire and obtain resistance for use on an ordinary lighting circuit. We find that we may use for element 11 ordinary resistance wire of about 80 No. 20 B. & S. gauge, and that this sized 85 wire, when coiled as illustrated in Fig. 2, may be used on an ordinary light or lamp circuit without external resistance, thus 90 producing high efficiency in the heating circuit. This form of heating element, however, becomes a dull red or slightly higher 95 heat when used on the ordinary circuit and gives a good supply of air heated to a temperature convenient for use in drying the 100 hair or other purposes.

Our experiments have shown that the flow of air from an ordinary desk type fan, if not changed by objects in front of the

fan, has substantially the form of a hollow cylinder, very little air coming off from points near the ends and near the centers of the blades. Our experiments have shown further that, largely for this reason, a heating element having a generally cylindrical or annular arrangement is the only one giving reasonable efficiency with a commercially practical type of heater when used with the ordinary type of electric fan. However, when the heating element is placed in the flow of air from such ordinary type fan, the distribution of the air flow is disturbed to some extent by the heating element itself and it is therefore desirable to check the flow.

15 The ends of the heating element or coil 11 are brought out through the supporting member 10 by means of rods 17 extending 20 through insulating blocks 18, 18, connection of the heating element 11 to the lead wires 19, 19 being made at points 20, 20.

Having thus described our invention, we claim:

25 1. A heating attachment for fans, comprising a heating element, a cylindrical member for supporting the attachment to

which said heating element is connected, said cylindrical member having an internal shoulder for limiting its movement with 30 respect to an internal support, and resilient means whereby said cylindrical member may be secured to a support.

2. An air heating attachment for fans, comprising a ring-like heating element, 35 means for supporting said element in a current of air flowing perpendicular to the plane of the ring, means for restricting the flow through the center of the heating element, and means for restricting the flow 40 of air outside of said heating element.

3. An air heating attachment for fans comprising a heating element, a cylindrical member for supporting the attachment and to which said heating element is connected, said cylindrical member having an internal shoulder for limiting its movements with respect to an external support, and springs secured to said cylindrical member, said springs having hooks formed thereon for 50 securing said cylindrical member to a support.

FRANK MORGAN HOWE,
CHARLES NAEGELI.
